BUBBLE CAP HOLD-DOWN DEVICE

John W. Kelley, East Chester, N. Y., assignor to
 The Lummus Company, New York, N. Y., a corporation of Delaware

Application December 12, 1947, Serial No. 791,343

3 Claims. (Cl. 261—114)

1

This invention relates to hold-downs for bubble caps and more particularly to such devices applied individually between each bubble cap and its respective riser.

It is a general object of the present invention to provide novel and improved forms of hold-downs for connecting bubble caps to their risers.

More particularly it is an object of the invention to provide individual bubble cap hold-down means operable from one side only of the supporting deck and which require only one man for application and/or removal.

An important object of the invention resides in the arrangement of the hold-downs to have minimum effect on the flow of gas or vapor through the deck opening and riser tube.

Another important object of the invention comprises the arrangement for complete removal of all parts of the hold-down means when separating the cap from the riser whereby cleaning is facilitated.

Still another important object of the invention resides in the provision of hold-down means which is removably fastened to the bubble cap and extends into openings in the wall of the riser tube.

One of the features of one embodiment of the invention consists in the use of an arch-like spring centrally secured to the bubble cap and having end-mounted pins engageable in radial holes in the wall of the riser tube.

An important feature of a second form of the invention consists in the use of a bolt extending diametrically through both the skirt of the bubble cap and the wall of the riser tube and secured rigidly to the former.

Other and further objects and features of the invention will be apparent to those skilled in the art on a consideration of the accompanying drawings and following specification, wherein are disclosed two exemplary embodiments of the invention, with the understanding that such modifications and combinations may be made therein as fall within the scope of the appended claims without departing from the spirit of the invention.

In said drawings:

Fig. 1 is a vertical central section through a bubble cap assembly and hold-down constructed in accordance with the present invention, taken on line 1—1 of Fig. 2 and illustrating in dotted lines the releasing movement of the arch spring forming a part of the hold-down mechanism;

Fig. 2 is a horizontal section taken on line 2—2 of Fig. 1 and looking upwardly as indicated by the arrows;

2

Fig. 3 is a fragmentary vertical section taken on line 3—3 of Fig. 2, illustrating one of the combined supports and spacers for positioning the cap in respect to the riser and deck; and

Fig. 4 is a view similar to Fig. 1 showing a modified hold-down means as well as a different supporting and spacing means for the cap.

Bubble caps are widely used in many processes, where it is necessary to provide intimate contacting between a liquid and a gas or vapor, and operate in cooperation with a flooded deck or plate and a tubular riser by causing the gas or vapor emerging under pressure from below the deck through the riser to pass beneath the surface of the liquid and bubble under the edge of the cap in the form of small bubbles which rise then through the liquid for further contact therewith. Bubble caps are arranged in multiple formation on plates or decks in towers or stills, which decks are usually spaced apart only sufficiently to permit a man to move between them for assembly and subsequent cleaning, which may even include removal of the bubble caps in order that the passages through the riser tubes may be cleaned.

Unless the bubble caps are extremely heavy, as would be achieved by casting them with excess metal, it is desirable to provide some hold-down means to prevent them from being bodily lifted off of their risers by the pressure of the gas or vapor ascending therethrough. Even though the caps are made of a considerable weight, certain gas pulsations or excess pressures occurring transiently may serve to lift one or more of them off of its riser. This would cause a free by-pass of gas or vapor and materially reduce the effectiveness of the deck on which it occurred.

Various suggestions have been made for bubble cap hold-downs but these have not been wholly satisfactory for various reasons. Some involve plates, bars, rods or the like, cooperating simultaneously with the top or a special lug on a plurality of caps and attached to the deck or to projections thereon by bolting or the like. Others are applied to individual caps and include wires, vertical bolts passing into spreaders spanning the deck opening for the riser and bearing against the under face of the deck, etc. Many of these restrict the flow through the riser and most are cumbersome, difficult to operate in the limitations of space available, and many require the presence of two workmen, one above the deck and one below, such as for positioning the spreaders or spiders and vertical bolts. Many of these devices are rendered ineffective or extremely difficult of

removal as the result of corrosion, erosion and/or the building up on their various surfaces of deposits of carbon, sludge and other chemical or waste constituents.

In accordance with the present invention simplified hold-downs are provided offering a minimum of difficulty in application and/or removal and which offer a minimum of resistance to the rising gases or vapors. Their construction is extremely simple, the cost of manufacture low, and replacement or removal rendered extremely simple and cheap under all conditions.

Referring now to the drawings for a better understanding of the invention, and first to the embodiment of Figs. 1, 2 and 3, there is illustrated at 10 a plate or deck forming a portion of a treating tower or still, such for instance as shown in the patent to Risdon, No. 1,711,656. Such a deck is provided at predetermined intervals with apertures 11 through which pass the riser tubes 12, conveniently fitting the apertures closely and having a liquid-tight connection thereto by virtue of a weld seam 13 surrounding the upper junction of the plate and tube.

Liquid is caused to flow across the plate in a manner as disclosed in the above patent by some similar approved method and maintains a level approximately that shown by the line L in Fig. 1, so that it will not overflow through the riser tubes under any conditions. Any conventionally accepted form of bubble cap 15 cooperates with each riser tube, as shown. Such a bubble cap, illustrated in Fig. 1, includes a substantially flat top 16 and circular vertical walls or skirt 17, the lower edge of which is appropriately dentated as at 18 to assist in breaking up the gas or vapor into the desired bubble size and disposition.

The form and construction of the deck, riser tube and bubble cap have no bearing on the present invention, and those illustrated are of more or less conventional form. Bubble caps are supported either directly from the deck, as for instance by extending some of the teeth 18 or providing other supports, but in many cases it is desirable to support them from the upper edge of their cooperating riser tube. The tube and cap are preferably co-axially disposed whether circular in cross-section or otherwise formed.

As shown in Fig. 3, a simple combined support and positioning bracket 20 is secured at intervals within the inner wall of the cap near its upper end, but any other satisfactory form of support may be used. Three is an appropriate number for the brackets for obvious reasons and is shown in Fig. 2. Each of these brackets is a metal plate notched as at 21 by the intersection of horizontal and vertical cuts. The horizontal surface of the three brackets cooperates with the upper edge 23 of the riser tube 12 to support each bubble cap at the proper distance above the deck plate to insure uniform immersion of the lower edges of all of the caps so as to make sure that none are starved and none over supplied with vapor. The vertical walls of the several brackets engage the outer wall of the riser tube 12 to insure co-axial disposition of the tube and cap. The caps are readily positioned by merely dropping them over the tubes.

In order to provide for attaching the cap fixedly to the riser tube, the latter is diametrically perforated as at 25 close to the upper edge in order to accommodate the pins 26 radially disposed and outwardly extending from the opposite free ends 27 of the spring 28. This spring may be generally defined as arch-shaped, having a flat central por-

tion 29, inclined connecting portions 30, and the substantially vertical depending ends 27 supporting the pins. If necessary the spring may be formed of corrosion resistant metal.

Such spring may be bent without the use of tools, for instance to the position shown in dotted lines at the left, to permit the pins to be inserted within the bore of the riser tube and moved about until they enter the holes 25, under the normal resiliency of the spring, to thereby position the spring within and above the tube where it does not interfere with the effluent gas. To further decrease the interference the ends of the spring are tapered, as seen at 32 in Fig. 2.

The center of the spring is perforated as at 33 to pass a bolt 34, which also extends through a perforation 35 in the center of the top 16 of the cap. The bolt may receive nut 37, which can be a separate part, but it is preferred that it be attached as by welding to the spring or its under face, thereby integrating the parts and permitting a single handed operation. The non-circular head of the bolt may seat on a suitable washer 36 to prevent escape of gas or vapor through hole 35. It will be noted that the spring and its cooperating bolt serves the sole purpose of a hold-down and is not relied on for positioning the cap either vertically or radially.

When assembling caps to tubes, the springs can initially be bolted to the caps and the whole applied to the risers, but a more convenient method consists in mounting the springs independently, where it is simpler to see and position the pins in respect to the holes and to subsequently apply the caps and bolts. The removal operation preferably includes the removal of the bolts and the caps and then the springs, all of which can be taken out of the tower for cleaning, leaving the interior of the riser tube entirely free and clear for the insertion of any cleaning instrument or brush which might be used. Likewise there are no outer obstructions so the exterior of the tubes can be readily cleaned. No part of the hold-down remains to interfere in any way whatsoever with the cleaning operation.

In Fig. 4 the disposition of the riser tube 50 and the bubble cap 52 is not substantially different from that described in connection with the first embodiment, but here has been illustrated a second form of cap mounting comprising the legs 53 depending from the cap below the edge of the teeth and resting on the surface of the deck 10. Such legs are shown as three in number and formed from strips of metal plate radially disposed against the inner wall of the skirt where they are attached as by welding. They have adequate radial dimensions to engage against the outer wall of the riser tube 50 to insure co-axial disposition of the cap and riser. Conveniently the lower ends of the legs are tapered on the inner face as at 54 to facilitate initial assembly and to reduce the amount of engagement with the deck, whereby minimum resistance to cross flow of liquid is produced.

In this construction diametrically arranged openings 55 are provided in the riser near its upper edge to accommodate portions of a hold-down bolt 56 which passes radially through openings 57 in the skirt of the bubble cap at the proper height to receive the same and is fastened thereto. One end of the bolt is provided with a fixed head 59 and the other end is received in a nut 60 which may or may not be attached to the wall of the cap skirt. As in the case of the first embodiment the circular rod which passes

through the openings is attached to the cap and extends into the holes in the riser. This form of the hold-down is extremely simple and in the event of corrosion or wear the bolts can be replaced from any standard stock. In both embodiments it will be seen that the whole application and/or removal of the caps can be effected from the upper surface of the deck by a single operator, thus facilitating removal and cleaning.

I claim:

1. A bubble cap assembly for use on a tray or deck comprising in combination a tubular riser element, a skirted bubble cap element extending over the upper ends of said tubular riser, spacer-support means carried by one of said elements and engaging the other for maintaining said elements in coaxial relation and supporting the cap element with its skirt edge spaced above the deck, said riser element having a plurality of widely and circumferentially spaced holes therethrough adjacent to the upper edge thereof, and spring means disposed in said cap element and detachably secured to the top thereof, said spring means having a plurality of resilient arms extending into the upper end portion of said riser element and spaced for alignment with the holes therethrough, the free end portion of each of said arms being provided with a fastening projection interengaging one of said holes.

2. A bubble cap assembly for use on a tray or deck comprising in combination a tubular riser element fixed to the deck at a hole therein, a skirted bubble cap element cooperating with said riser and extending over the upper end thereof, means on one of said elements to position the cap coaxial to the riser and to support the same with its skirt edge spaced above the deck, said riser having opposite radial holes therethrough adjacent the upper edge thereof, an arched spring having resilient arms extending into the upper end of said riser element and adapted to cooperate with the walls thereof, a pin on the

free end of each arm for reception in one of said holes, and means joining said spring and cap above the level of the top edge of the riser.

3. A bubble cap assembly comprising a deck-mounted riser tube having circumferentially spaced perforations near its upper edge, a skirted cap over said tube, combined supports and spacers secured to the inner face of the skirt and arranged to engage the upper edge of the tube to support the cap thereabove in coaxial relation therewith, a flat spring element of maximum dimension in unstressed condition substantially equal to the inner diameter of said riser and having an axis of flexure in a horizontal plane whereby said spring is restrained from exerting any substantial force in a vertical plane, a center perforation in said spring, a center perforation in said cap, a bolt passing through said center perforations for attaching the cap to the spring, said spring element having downturned ends and a pin on each of said ends adapted to be snapped into one of said perforations to secure the cap to the tube, whereby said spring when assembled is in substantially unstressed condition.
